(57) **CLAIM**

The ornamental design for a shoe, as shown and described.

DESCRIPTION

FIG. 1 is a front perspective view of a shoe showing my new design;

FIG. 2 is a side view thereof;

FIG. 3 is an opposite side view thereof;

FIG. 4 is an opposite front perspective view thereof; and,
FIG. 5 is a top view thereof.

The broken lines immediately adjacent to the shaded area define the bounds of the claimed design and form no part thereof. The ten unshaded broken line circles within the shaded area represent eyelets and form no part of the claimed design. The broken lines depicting the remainder of the shoe show features that form no part of the claimed design.
